Primary Examiner—Melanie H Tung*Assistant Examiner*—Lavone D Tabor(74) *Attorney, Agent, or Firm*—Knobbe, Martens, Olson & Bear, LLP(57) **CLAIM**

The ornamental design for a toothbrush base, as shown and described.

DESCRIPTION

FIG. 1 is a top, front, and left side perspective of a toothbrush base embodying my new design.

FIG. 2 is a bottom, rear, and left side perspective thereof.

FIG. 3 is a front elevation view thereof.

FIG. 4 is a rear elevation view thereof.

FIG. 5 is a left side elevation view thereof.

FIG. 6 is a right side view thereof.

FIG. 7 is a top plan view thereof; and,

FIG. 8 is a bottom plan view thereof.

Shown in phantom lines are selected portions of supports and a receiving area for receiving a toothbrush which form no part of the claimed design.
